UNITED STATES PATENT OFFICE.

FREDERICK C. OVERBURY, OF HILLSDALE, NEW JERSEY, ASSIGNOR TO THE FLINT-KOTE COMPANY, OF BOSTON, MASSACHUSETTS, A CORPORATION OF MASSACHUSETTS.

MACHINE FOR MAKING ORNAMENTAL ROOFING.

1,419,169.

Specification of Letters Patent. Patented June 13, 1922.

Original application filed March 6, 1917, Serial No. 152,492. Divided and this application filed November 3, 1921. Serial No. 512,502.

To all whom it may concern:

Be it known that I, FREDERICK C. OVERBURY, a citizen of the United States, residing at Hillsdale, in the county of Bergen 5 and State of New Jersey, have invented new and useful Improvements in Machines for Making Ornamental Roofing, of which the following is a specification.

This invention has relation to prepared 10 roofing elements and more particularly to those which are designed to be separately arranged on the roof in simulation of wooden or mineral shingles or tiles. Usually such elements are in the form of what are termed 15 shingles or shingle strips, and they are more or less flexible, being cut from sheets of prepared weatherproof material. In order that such elements may be used on dwellings and high grade structures, they have 20 heretofore been ornamented, and incidentally rendered more fire-proof, by the application to the surface thereof of crushed mineral such as slate, earthenware tile, granite and the like, and indeed such crushed minerals 25 of different colors have been so placed on the elongated sheets of roofing material to constitute conventional predetermined designs. Ordinarily, however, the shingles and shingle strips have had the surface 30 thereof coated with crushed mineral of one color or another so that the entire area of such elements, when placed on the roof, presents an unvarying color, shade or tint. While the provision of such shingles or 35 shingle strips have greatly enlarged the scope of their usefulness, nevertheless they have failed to meet the demands of those who are insistent upon certain æsthetic and ornamental effects. That is, notwithstanding 40 that mineral coated roofing elements have attained a certain vogue and have been used in large quantities on the roofs of dwellings, yet when laid they present a flat and unvarying and hence uninteresting 45 monotonous appearance which is offensive to those who have artistic tastes.

Natural building materials, such as wooden shingles, when exposed to the weather, even when stained, are so acted 50 upon by the wind and weather, as to present different shades or tints or colors in

different unpredetermined areas, just as seam-faced granite because of its natural formation presents to the eye beautiful varied color tones.

I have discovered, as pointed out in my application, Serial No. 152,492, filed March 6, 1917, of which this is a division, that it is possible to destroy the monotonous effect produced on the eye by the mineral coated 55 elements when laid on the roof, by employing crushed minerals of different colors and shades, and so applying the same to the elements in the process of manufacture, as to provide variable areas having one color and 60 variable areas of other color with intervening areas where the colors blend or shade from one to the other, these various areas constituting no predetermined or related designs but occurring very much as they occur 65 in seam-faced granite or other natural materials. This result may be accomplished by the employment, for example, of green and red crushed slates, which are delivered to the sheet of adhesive-coated fabric in such 70 way that portions or areas on the sheet are coated only with green slate, other portions or areas with red slate, and the intervening portions or areas with a mixture of the two 75 differently-colored materials.

Upon the accompanying drawings, I have 80 illustrated conventionally a form of apparatus embodying the present invention which may be employed in manufacturing roofing elements such as described.

Referring to said drawings,

Figure 1 represents conventionally instrumentalities embodying one form of my improvements and which may be employed for the manufacture of the shingle strips.

Figures 2 and 3 represent the instrumentality for applying the differently colored crushed mineral materials.

Figure 4 represents an attempt to illustrate the sheet of material and to show the 95 areas of different colors thereon.

Figure 5 represents a longitudinal section through a valve by which the crushed mineral is fed to the machine shown in Figures 2 and 3.

Figures 6 to 9 inclusive represent transverse sections through the multiple valve.

Figure 10 represents a cross section showing the valve closed.

Figure 11 illustrates the end of the valve mechanism.

5 Figures 12 and 13 illustrate another form of valve mechanism which may be used.

It will of course be understood that the drawings are more or less diagrammatic and show the several instrumentalities more or 10 less conventionally, and that the latter may be of any approved construction or design. The instrumentality first in order of operation is an apparatus for saturating or impregnating a sheet of fibrous material such as 15 felt or the like with the usual waterproofing composition of a hydrocarbon or bituminous nature. This is indicated at A, and it may comprise a suitably heated tank or vat 20 for containing said compound, through which 20 the sheet *a* is drawn from a roll *b*. Squeeze rolls 21 remove the surplus compound from the now saturated sheet prior to its passage to the next instrumentality.

The second apparatus is indicated at B, 25 and it is an apparatus for applying to one face of the saturated sheet a coating of pitch or asphalt having the desired consistency and melting point at ordinary temperatures. This material is applied in a molten or plastic adhesive condition and extends from edge 30 to edge of the sheet. Between the two instrumentalities A and B may be arranged additional cooling rolls if desired. As shown, the apparatus B has the cooling rolls 22, and 35 the rolls 23, 24, in connection with the latter of which there is the receptacle 25 for the molten pitch or asphalt, which is spread on the surface of the impregnated sheet.

The third instrumentality is indicated at 40 C and applies the different mineral materials to the sheet while the bituminous coating thereon is still adhesive. The particular description of this machine is given herein-after.

45 The fourth instrumentality D is the machine which cuts the sheet into the roofing elements. Any suitable machine may be used for this purpose for either longitudinally slitting the sheet and transversely severing 50 it at intervals to form shingles of oblong or other shapes, or else cutting it into shingle strips such as shown in Letters Patent No. 1,150,298, dated August 17, 1915. For example, the machine shown is similar to that 55 shown and described in my Letters Patent No. 1,182,417, dated May 9, 1916, and includes the feeding rolls 26, the cutting rolls 27, and the chopping knife 28 for forming the sheet *a*, the shingle strip *c* having the 60 spaced tabs or projections *d*. In lieu of the machine thus conventionally illustrated, I may employ any other equivalent machine for producing the detached roofing elements.

Between the third and fourth instrumentalities may be arranged a festooning and

cooling mechanism of any suitable sort, although I have not thought it necessary to illustrate the mechanism as it is well known.

Returning now to the surfacing machine C, I have shown it as provided with cooling 70 rolls or cylinders 29, and also with the rolls 30, 31, to the former of which the coated fabric passes from the machine B, while the coating is still in an adhesive condition.

Arranged in operative proximity to the roll 75 30 is a trough 32 which extends from end to end of the roll and to which the differently colored surfacing minerals are delivered,

and from which it is fed to the coated fabric. This trough has the feeding roll 32. 80

This material adheres to the coated sheet and is partially embedded therein as the sheet passes between rolls 30 and 31, the surplus mineral material falling back to the trough

as the sheet passes over roll 31 to the cooling 85 rolls or drums 29. The differently colored

surfacing minerals are contained in separate compartments or receptacles and are de-

livered in batches to the trough. A hopper

33 is divided longitudinally by a partition 34 90

into two compartments 35, 36, of which the

former may contain for example red crushed

slate, and the other green crushed slate.

These compartments converge at their lower

ends to a valve casing 37 in which I have

shown a multiple valve 38. This valve has

four passageways for the mineral material

therethrough, two as at 40 and two as at 41,

those at 40 and 41 alternating. These are so

arranged that, when the valve passages 40 100

communicate with compartment 36, those at

41 communicate with compartment 35 and

vice versa. Thus at the same time two

streams of red slate are being delivered to

certain portions of the trough and two 105

streams of green slate to other portions there-

of. On rocking the valve to its other opera-

tive positions, the streams of red slate are cut

off and are followed by streams of green

slate, and the streams of green slate are cut 110

off and are followed by streams of red slate.

Thus there are delivered to the troughs dif-

ferent batches of colored mineral, and there

are strata of red in each batch with inter-

vening strata of green. Where these batches

115 meet, the materials mingle or mix as will be

well understood, as there is nothing to sep-

arate them. Hence, as the coated sheet passes

the trough, unconventional patches of green

and red slate will be applied respectively to

120 different portions or areas of the sheet, be-

tween which areas will be areas in which the

two colors will be mixed or blended without

any lines of demarcation. Thus the sheet

125 will present a more or less mottled appear-

ance as indicated conventionally in Figure 4.

The valve may be operated by hand, but,

preferably, it may be operated automatically.

To this end, I may affix to the valve a weight-

ed arm 43 connected by a rod 44 to a lever

130

- 45 oscillated by a cam 46. The latter may be driven by a belt 47 and pulleys 48, 49, the latter being operated by roll 30. The rod 44 is shown as detachably hung on a pivot 50 5 on weighted arm 43, but, by lifting the latch 51, the rod 44 may be disconnected therefrom, allowing the arm 43 to drop to move the valve in position to cut off both streams of mineral to the trough, as indicated in Figure 10. When the rod is disconnected, the valve may be operated manually. The valve mechanism, which I have illustrated and described, may be replaced by any mechanical equivalent therefor, which will readily suggest itself. For example, in Figures 12 and 13 I have illustrated the two large hoppers or receptacles 60, 61, from which lead the spouts 62, 63, for the purpose of delivering the differently colored grit to the hopper 32. 20 These spouts are controlled by sliding valves or gates 64, 65 which may be operated manually or automatically as desired. Other specific forms of valve mechanism may be employed if desired.
- 25 What I claim is:
1. Apparatus for making variegated roofing, comprising means for saturating a sheet of fibrous material, means for applying a layer of plastic asphalt to the face thereof, 30 a trough for showering crushed slate on the plastic coating, separate receptacles for masses of differently colored slate, and controlled means for controlling the supply of slate from said sources to said trough.
  2. Apparatus for supplying crushed slate 35 to a sheet of coated roofing, comprising separate receptacles for containing masses of slate of different colors respectively, a trough for showering the sheet with such slate, and controlled valves for causing the simultaneous delivery to different portions of said trough of slate from certain of said receptacles to said trough.
  3. Apparatus for supplying crushed slate to a sheet of coated roofing, comprising separate receptacles for containing masses of slate of different colors respectively, a trough for showering the sheet with such slate, and mechanism for delivering slate from certain of said receptacles alternately to said trough. 50
  4. Apparatus for supplying crushed slate to a sheet of coated roofing, comprising separate receptacles for containing masses of slate of different colors respectively, arranged in two series, a trough for showering 55 the sheet with such slate, and controlled means for delivering slate to said trough from each of said receptacles intermittently and from certain of them simultaneously.

In testimony whereof I have affixed my 60 signature.

FREDERICK C. OVERBURY.
